ATTORNEY

UNITED STATES PATENT OFFICE.

HUGH P. DALY, OF WHEELING, WEST VIRGINIA, ASSIGNOR OF TWO-THIRDS
TO RANDOLPH STALNAKER, JR., OF SAME PLACE.

CAR-COUPING.

SPECIFICATION forming part of Letters Patent No. 251,703, dated January 3, 1882.

Application filed November 14, 1881. (No model.)

To all whom it may concern:

Be it known that I, HUGH P. DALY, of Wheeling, in the county of Ohio and State of West Virginia, have invented certain new and useful Improvements in Car Couplers; and I do hereby declare the following to be a full, clear, and exact description of the invention, such as will enable others skilled in the art to which it pertains to make and use the same.

10 My invention relates to an improvement in car-couplers, the object being to provide a car-coupler of such construction that it may be employed either as hand or an automatic coupler, the parts to be simple and durable in construction and of small first cost in manufacture.

With these ends in view my invention consists, first, in a car-coupler, in the combination, with a coupling-link, of a draw-head and a coupling-pin adapted to be inserted in the draw-head either vertically or horizontally and engage with the coupling-link.

My invention further consists in the combination, with a draw-head having coupling-pin holes in its sides and a removable coupling-pin adapted to be secured in the draw-head in a horizontal position, of a coupling-link having hooked ends and adapted to automatically engage with the coupling-pin.

30 My invention further consists in certain other features of construction and combinations of parts, as will hereinafter be explained, and pointed out in the claims.

In the accompanying drawings, Figure 1 is a view in perspective of my invention. Fig. 2 is a longitudinal section. Fig. 3 is a side elevation of the coupling-pin, and Fig. 4 is a plan view of the same.

40 A and B represent the draw-heads of two adjacent cars of a train. These draw-heads are of the ordinary form, and are each provided with the vertical holes a a' , for the insertion of a coupling-pin, C. Horizontal holes b b' are also formed in the sides of the draw-head, where 45 by the coupling-pin C may be inserted through the draw-head horizontally, and may be retained against displacement by means of a linch-pin, D, or any suitable device may be used for this purpose.

E is a coupling-link, preferably of the length 50 of ordinary coupling-links, and provided with an elongated slot, F, whereby it is adapted to be used as an ordinary coupling-link and have the coupling pins engage in the elongated slot F when inserted vertically through the draw-head, as is usual in the ordinary form and construction of draw-heads. Coupling-link E is constricted with the hooks G G formed on its opposite ends. Each hook has its outer face beveled, as at c, and provided with a flat bearing, d, which is located below the lower central portion, e, of the link. The recess f of the hook is of such form as to receive the body of the coupling-pin C. To the upper face of each draw-head is secured a spring, H, for a purpose hereinafter described.

Having described the construction and relative arrangement of parts of my improved car-coupling, I will now describe its operation.

When the coupling is to be used as an ordinary hand-coupler the coupling-pin is inserted through the vertical holes of the draw-head and through the elongated slot in the link. This may be done when it is desired to couple a car provided with my improved coupler with a car furnished with an ordinary draw-head and adapted to be coupled by an ordinary link. When it is desired to couple two cars automatically the coupling-pin is inserted horizontally 75 through the draw-head and the coupling-link 80 coupled to the draw-head of the other car. As the cars come together the beveled end c of the link strikes the coupling-pin and rides over it, the spring H pressing the end of the link down so that the coupling-pin will be received in 85 the recess f of the link and be prevented from disengagement therefrom by means of the spring H.

This construction and arrangement of parts is simple, durable, and certain of operation, and, 90 further, the coupling has sufficient vertical adjustment to enable cars of different height to be coupled either automatically or by hand. When the coupling is automatic the links have an extended lateral bearing on the coupling-pin, and prevent any undue swaying of the 95 cars while in motion.

Cars of ordinary construction may be pro-

vided with my improvements at a small first cost. The ordinary draw-head may have the coupling-pin holes formed in its sides, and a spring secured within the mouth of the draw-head. Then, by employing a link constructed in the manner described the cars may be coupled either by hand or automatically, as desired.

Having fully described my invention, what I claim as new, and desire to secure by Letters 10 Patent, is—

1. In a car-coupler, the combination, with a draw-head having holes a and $b b'$, of a coupling-pin, C, arranged horizontally within the draw-head, and a coupling-link, E, having 15 hooks G G and an elongated slot, F, substantially as set forth.

2. In a car-coupler, the combination, with a draw-head having holes, as described, of a coupling-link having an elongated slot, F, and hooks G, a coupling-pin, C, passing transversely 20 through the draw-head, and a retaining device, D, substantially as set forth.

In testimony whereof I have signed this specification in the presence of two subscribing witnesses.

HUGH P. DALY.
